UNITED STATES PATENT OFFICE.

CHARLES E. ROBERTS, OF CHICAGO, ILLINOIS.

BOLT-THREADING MACHINE.

SPECIFICATION forming part of Letters Patent No. 369,963, dated September 13, 1887.

Application filed September 28, 1886. Serial No. 214,724. (No mode!.)

To all whom it may concern:

Be it known that I, CHARLES E. ROBERTS, a citizen of the United States, residing in Chicago, in the county of Cook and State of Illinois, have invented a new and useful Improvement in Bolt-Threading Machines, of which the following is a specification.

In this invention one of my main objects has been to obtain for the screw or thread cutting dies a full and ample supply of oil at all times while they are operating, and for this purpose I arrange the bolt-holder and the dies in a vertical line upon hollow spindles, through which a constant and uniform flow of oil may be kept up. One of these spindles rotates first in one direction to thread the bolt and then in the reverse direction to draw it out from the die. This reversal of movement is automatic; but the motion may continue for an unlimited time after the bolt is freed from the die without injury and until the attendant is ready to remove the bolt and insert a fresh one.

The invention further embraces the details of construction and the operating mechanism hereinafter fully described.

The accompanying drawings show at Figure 1 a front elevation, and at Fig. 2 a side elevation, of my invention. Fig. 3 is a central vertical section through the spindles. Fig. 4 is a plan of the parts shown in Fig. 3. Fig. 5 is a plan of the reversing-clutch for changing the direction of the rotation of the dies. Fig. 6 is a section of the parts shown in Fig. 5. Fig. 7 is a plan of the nut-holding spindle upon the line 7 7 of Fig. 3, and Fig. 8 is a bottom view thereof.

In said drawings, W represents the frame of the machine; W', the driving-pulley, and W² the shaft upon which said pulley is mounted.

W³ is a tank or receptacle for the collection of the oil and cuttings from the threading-die, and W⁴ is a pipe leading from this receptacle to the top of the machine, through which pipe the oil is returned to do duty again by any suitable pump inserted therein, as at W⁵, and driven from the shaft W², as shown. The pipe W⁶ may be employed to return to the tank any excess of oil which may be raised by the pump, and both it and the pipe W⁴ may be supported by standards W⁷.

The bolt to be threaded is placed in the ma-

chine with its head uppermost and within the socket m, formed upon the lower end of a hollow vertical spindle, A, which I term the "inner" spindle, because it is placed inside of a surrounding spindle, A'. This outer spindle fits in a cross-head, A², which is supported in the frame W. At either side of the cross-head A² rise guides A³. Lateral arms A⁴ upon the spindle A' extend to these guides, and are provided with anti-friction rollers a and pins a', which embrace said guides upon opposite sides and prevent any rotation of the outer cylinder, the rollers being placed upon the sides of said guides against which the strain caused by the threading is exerted. As soon as the bolt is positioned in the socket m, the operator depresses the lever B, fulcrumed in the link B', and thereby lowers both the spindles until the bolt-blank enters the threading-die n upon the upper end of a spindle, C, also hollow, placed immediately below and in line with the spindles A and A', and rotating in bearings in the frame, and supported vertically by the collar C'. This spindle C is rotated by a bevel-gear, C², upon its lower end, such gear receiving power from one or other of the gears C³ C⁴, with which it constantly meshes, but only one of which communicates power at a time. Being loosely mounted upon the main shaft W², these gears C³ and C⁴ are alternately engaged and positively actuated from said shaft by the sliding clutch C⁵, located between them upon the shaft and feathered thereto, as at c.

When the bolt has been lowered into the die, the operator throws the clutch C⁵ into engagement with that one of said gears C³ C⁴ which will actuate the spindle C in the right direction (as, for instance, in the machine illustrated with gear C³) by means of the lever C⁶, oscillating upon the center c', and the operation of threading is begun. This creates at once such friction between the bolt-head and the socket m as results in the gradual pulling down without rotation of the upper spindles with the bolt as the latter is drawn into the die, and such downward movement is continued by both spindles until the regulating-screw A⁶ in one of the lateral arms A⁴ strikes the cross-head A², after which the downward course of the inner spindle is protracted until the clutching projections a² upon the flange a'

of the inner spindle have drawn out from contact with the clutching projections a^4 upon the ring a^5 , secured to the outer spindle. Upon this release taking place the inner spindle and the bolt become free, so that they rotate with the threader until one of the cams a^6 , projecting from the inner spindle, comes in contact with the crank-arm D upon the upright shaft D' and oscillates said shaft, causing the lower crank, D², upon said shaft to act against the spring-lever D³ and bring it to the position shown in Fig. 5. This spring-lever is a horizontal one, being secured at d to a stationary part of the machine, and having an inclined surface, d', upon which said crank D² acts, and a bent-up end, d², which acts as a retainer for said crank. Said spring also carries a projection or stop, d³, which up to the time the spring-lever is acted upon by the crank contacts with the pin d⁴ upon the lever C⁶, thereby retaining the clutch in engagement with the gear C³; but the forcing of the spring-lever into the position shown in Fig. 5 releases the contact of d³ with d⁴ and allows the lever C⁶ to swing in obedience to the spring d⁵ and carry the clutch into engagement with the gear C⁴, thereby reversing the rotation of the die-carrying spindle. In the meantime, the cam a⁶ having passed the crank-arm D, the shaft D' is allowed to return to its first position under the impulse of the spring-lever D³, and as the reversing of the threader withdraws the power transmitted through the bolt to the spindle A, said spindle is then allowed to close its clutch with the spindle A' under the power of the spring a⁷.

The reversing of the threader and the stopping of the rotation of the bolt-holding spindle results in forcing the bolt out from the die, or, in other words, unscrewing it therefrom. This transmits a lifting force to the upper spindles through the bolt, which of course ends as soon as the bolt has passed entirely out of the die. The rotation of the die may then continue without injury to the bolt until the attendant finds time to remove the latter.

I find it useful to connect a counter-weight, E, to the upper spindles through the rope e, passing over the pulley E' and hook e'. The lifting of the spindles is thereby rendered very easy, and by balancing them very nearly they are prevented from moving in either direction through gravity alone.

It will be noticed that the oil is conducted from the pipe W⁴ to the interior of the upper spindle, A, by the pipe W⁸, and that the passages w allow it to flow therefrom onto the bolt. In this manner the bolt may be kept completely enveloped in a sheet of flowing oil at all times without difficulty. A valve, W⁹, may be inserted in pipe W⁸ to control the flow. From the die the oil, together with the cuttings, may and preferably does flow down through the lower spindle, and is discharged thence into the tank described.

As it may be desirable at times to deprive the lower spindle of all motion, I may lock

the clutch C⁵ positively in an intermediate position without engagement with the gears at either side by means of a spring-bolt, f, confined in the lever and adapted to be passed up into the cavity f' in the part of the machine-frame upon which the lever is journaled. This bolt is operated by the pin f'', and also fastened down by the entrance of said pin within the lateral enlargement of the slot through which it projects.

It will be noticed that the bolt-holding spindles are provided with a single bearing in the frame at about their vertical center. This leaves the lower ends free to yield to some extent to lateral strains, or, in other words, renders them slightly elastic. The rollers a are located on opposite sides of the spindles and receive equal portions of the strain caused by the threading, so that if the spindles turn at all under that strain they turn upon their axial line. In this manner the forces are equalized and the spindles do not wear out of true.

It will be further noticed that the mechanism for reversing the rotation of the die does not operate until after the threading is complete. This feature enables the clutch to be released from one gear and shifted to the opposite one when there is but little power required at its hands, and the shifting becomes an easy matter.

The threading is completed, of course, at the time the bolt begins to rotate with the die.

It will be noticed that the outer spindle, A', being provided with anti-friction rollers bearing upon its guides A³, is less affected by friction with said guides under the strain caused by the threading than is the bolt-head in its socket m; also, that the clutch-faces connecting the inner and outer spindles are at a considerable remove from the center of the spindles, while the bolt-socket is located at such center, and hence the friction between the bolt and socket will be greater than that between the clutch-faces, and the latter will more readily separate than the former.

I claim—

1. The combination of the bolt-holder and threading-die, each carried by hollow spindles arranged vertically, and a conduit for leading the oil to the upper one of said spindles, substantially as specified.

2. In a bolt-threading machine, the bolt-holding spindles, the outer one of which has lateral arms upon opposite sides, provided with anti-friction rollers a, in combination with guides for said rollers, substantially as specified.

3. In a bolt-threading machine, the combination of vertically-moving bolt-holding inner and outer spindles, a reversibly-rotating threader, and means, substantially as shown, for effecting the change of movement of the threader.

4. In combination with the threading-spindle, the gear C², borne on said spindle, the gears C³ C⁴, loose upon their shaft, the sliding

- double-faced clutch feathered to the same shaft, and a lever for shifting said clutch, a bolt-holding device arranged in line with and movable toward said threading-spindle, substantially as specified.
5. The combination of a reversibly-rotating threader, the gears for driving the same, and the clutch for actuating the gears with the bolt-holding spindles, one of which carries the socket m , and both of which are reciprocated by power transmitted through the bolt, the oscillatory shaft D' and its arms, operated by one of the spindles, and the spring-lever D^3 , substantially as specified.
10. A bolt-holding spindle which both slides and rotates, a sliding non-rotating spindle surrounding said bolt-holding spindle, and clutching devices upon said spindles for locking the inner spindle against rotation, in combination with the rotating threader imparting said movements to said spindles by the power or friction transmitted through the bolt being threaded, substantially as specified.
15. The sliding bolt-holding spindles A and A' , having clutching devices, as specified, and the regulating-screw A^5 , stopping the descent of the outer spindle, in combination with the rotating threader drawing down said spindles by the power or friction exerted upon the bolt, substantially as specified.
20. The sliding bolt-holding spindles A and A' , having clutches, as specified, the inner spindle being free to rotate when freed from the clutch, and having cam a^6 , in combination with the oscillatory shaft, the threader, and the intervening mechanism for reversing the latter, substantially as specified.
25. In a bolt-threading machine, the combination of the sliding bolt-holder spindles A and A' , having the regulating-screw A^5 , with the threader, substantially as specified.
30. The inner spindle having the cam a^6 , the oscillatory shaft and its cranks, the spring-le-
- ver acted upon by said shaft, the clutch-shifting lever and its spring, and the clutch, in combination with the threader and its actuating-gearing, substantially as specified.
35. The combination of a reversibly-rotating threader with the bolt-holding spindles, one of which carries the socket m , and both of which are reciprocated by power transmitted through the bolt, substantially as specified.
40. In a bolt-threading machine, the combination, with the spindles A and A' , of a counter-weight, substantially as and for the purpose set forth.
45. The spindles A and A' , one of which carries the bolt-socket m , the clutching devices upon said spindles, and the spring a^7 , acting to close the clutching devices, in combination with the rotating threader, from which the power to separate said clutch is transmitted through the bolt, substantially as specified.
50. The combination, with inner reciprocating spindle, A , having centrally-located socket m , of outer spindle, A' , surrounding spindle A , and provided with exterior arms having anti-friction rollers bearing upon its guides A^8 , whereby the friction between the outer spindle and its guides due to the threading operation is rendered less than that between the bolt-head and the socket m , substantially as specified.
55. The combination, with inner reciprocating spindle, A , and having socket m for the bolt-head, of outer spindle, A' , clutch-faces connecting said spindles located outside the bolt-socket, whereby the friction is less between the clutch-faces than between the bolt-head and its socket, so that the clutch-faces will separate before the bolt withdraws from its socket, substantially as specified.
